UNITED STATES PATENT OFFICE.

GORDON KALTENBACH, OF BIRMINGHAM, ENGLAND.

COMBINED BUTTON AND FASTENER.

1,334,656.

Specification of Letters Patent. Patented Mar. 23, 1920.

Application filed March 8, 1919. Serial No. 281,450.

To all whom it may concern:

Be it known that I, GORDON KALTENBACH, a subject of His Majesty the King of Great Britain and Ireland, residing at 79 Gillott road, Edgbaston, Birmingham, England, have invented new and useful Improvements in Combined Buttons and Fasteners, of which the following is a specification.

This invention has reference to a combined button and fastener which is designed to attach to garments and the like without sewing and the object of my said invention is to provide a combined button and fastener which can be readily applied and which is adapted to pierce the necessary hole for the button shank and thus obviate the necessity of using any instrument for that purpose. Moreover when my combined button and fastener is affixed to a garment it can readily be unfixed and again be similarly affixed for use in another position or on a different garment.

According to this invention the button has a single stem or shank which has a knobbed or enlarged end and fitting on this stem there is a sheath like fastener which is pointed at one end and is adapted to engage with the knobbed or enlarged end of the shank and can either be turned thereon to stand at right angles to the shank or can be turned so as to inclose the shank and be in a line therewith. The said sheath is slotted longitudinally from its open end to about the center to permit of its turning at right angles to the shank as aforesaid.

In using the combined button and fastener the sheath is turned so as to be in line with the shank and then the sheath part inclosing the shank is forced pointed end first through the fabric and is then drawn forward through a short space on the other side of the fabric and turned on the shank at right angles thereto so as to thereby effectually prevent the button shank from pulling out of the hole. To remove the button the sheath is again turned to stand in line with the shank and then the button can be pulled forward with the sheath out of the hole in the garment.

My invention is illustrated by the accompanying drawings of which—

Figure 1 is a front elevation partly in section of a combined button and fastener constructed in accordance with this invention;

Fig. 2 is a side elevation of the same partly in section;

Figs. 3, 4 and 5 are also part sectional side elevations of my invention to illustrate the method of using the same; and

Fig. 6 shows the thin sheet steel blank for forming the sheaths.

A is an ordinary button provided with a rigid single stem or shank B made with a knobbed or enlarged end 1. C is the said sheath like fastener which is pointed at one end 2 and is adapted to engage with the knobbed or enlarged end 1 of the shank B which enters the open end 3 of the sheath C and the latter is secured to the shank B by the end 3 of the sheath being slightly in-turned so as to prevent the sheath from coming off the shank until the shank and sheath are pulled with sufficient force in opposite directions as to cause the enlarged or knobbed end 1 to pass through the in-turned mouth 3 of the sheath. The sheath C is for about half its length from the ends say to the central part 4 made with a longitudinal slot 5 which is preferably slightly narrower than the diameter of the neck 6 of the shank B and this slot 5 terminates in an enlargement 4 which is slightly larger than the neck 6 of the shank but less than the knob 1 so that the neck will fit easily in this enlargement 4. Thus the sheath C can either occupy a position in line with the shank B as in Figs. 1, 2, 3, and 4 or the sheath C can be turned at right angles to the shank B and be pushed endwise so that the shank B will travel along the slot 5 as far as the central part 4.

When attaching the button fastener A with its shank B and fastener C as to the portion 7 of a garment, the fastener C has first to be slipped up along the shank B, as in Fig. 3 so that the shank and sheath will then be substantially rigid and then by pressing on the button the pointed end 2 of the sheath will pierce the material 7 and be forced through the same to the other side thereof, and now the sheath C has to be pulled forward until arrested by the in-turned end 3 of the sheath coming into contact with the knob 1 as shown in Fig. 4. Now the sheath has to be turned at right angles to the shank B as in Fig. 5 and the button is effectually secured to the material 7.

The button with the sheath can readily be

removed from the garment by first sliding the sheath C along until the open end 3 of the sheath is at the knob part 1 of the shank so that the sheath can now be turned in line 5 with the shank and the button and sheath pulled back through the hole in the material 7.

The longitudinal slot 5 in the sheath is 10 preferably made very slightly less in width than is the diameter of the shank B so that the sides of the slot are slightly pressed apart by turning the sheath to its right angled position as aforesaid and sliding the shank along the slot to the enlarged part, 4, 15 so that as the shank enters this enlarged part 4 the sides of the slot spring toward one another again to their normal position and the neck and head of the shank are thus temporarily retained in the central part 4.

20 Said shank B and sheath C are preferably circular in cross section as illustrated or they may be comparatively flat and moreover as a modification the sheath may be permanently attached to the button shank so as not to be 25 removable therefrom.

In order to afford the sheath C a firmer hold on the fabric an ordinary small washer 8 may if desired be threaded on and along the sheath and off the same on the button 30 shank against the fabric 7 after the sheath has been pushed therethrough as shown in Fig. 4 so as to be situated between the fabric and the sheath as indicated in Fig. 4, and now when the said sheath C is turned on the 35 button shank B so as to be at right angles thereto as aforesaid to secure the button, the washer 8 will be situated between the sheath C and the fabric 7 and will afford a large bearing against the latter.

40 The sheath C can conveniently be made from a sheet steel or other suitable sheet metal blank 9 which is raised and bent up

into the required sheath like form as aforesaid. The blank for forming the sheath C illustrated on my drawings is shown in Fig. 45 6 and marked 9.

It is to be understood that by the term "button" I include not only buttons which are fixed to one part of a garment to be engaged in a button hole of the other part, but 50 also such buttons as are used as dress ornaments, or to distinguish military and naval and other uniforms, or which serve as badges, said buttons having their heads or front parts made of various shapes and 55 ornamented or furnished with various devices as is well understood.

What I claim as my invention and desire to secure by Letters Patent is:—

1. The combination with a button furnished with a single stem or shank having a knobbed or enlarged end, of a sheath like fastener engaging said shank and made with one piercing end and the other end open through which the button shank protrudes 60 said sheath being slotted longitudinally for a certain distance from said open end so as to permit of the sheath being turned to about right angles with the shank and slid along the same for the purpose and substantially as set forth.

2. A combined button and fastener according to claim 1 in which the longitudinal slot of the sheath terminates in an enlargement between the ends of the sheath and the 75 sides of said slot are so constructed as to be sprung apart slightly by the moving of the button shank along the same and to then spring inwardly to temporarily retain the button shank in the said enlargement, substantially as set forth.

In testimony whereof I have signed my name to this specification.

GORDON KALTENBACH.
